UNITED STATES PATENT OFFICE.

PERCIVAL W. ELLIOTT, OF READING, ASSIGNOR TO THE HIGHLAND
FOUNDRY COMPANY, OF BOSTON, MASSACHUSETTS.

COOKING STOVE, RANGE, &c.

SPECIFICATION forming part of Letters Patent No. 551,116, dated December 10, 1895.

Application filed May 31, 1895. Serial No. 551,075. (No model.)

To all whom it may concern:

Be it known that I, PERCIVAL W. ELLIOTT, a citizen of the United States, residing at Reading, in the county of Middlesex and 5 State of Massachusetts, have invented a new and useful Improvement in Cooking Stoves, Ranges, &c., of which the following is a full, clear, and exact description, reference being had to the accompanying drawings, forming 10 a part of this specification, in explaining its nature.

The invention is an improvement upon that described in my application for Letters Patent of the United States filed July 30, 1894, 15 Serial No. 518,911; and it consists in the arrangement and organization of a coal stove or range, a gas-stove combined with the coal-stove for joint or separate use, as described in my said application, and a hot-water tank 20 or boiler connected with the water-heating system of the coal-stove and with a water-heating system of the gas-stove, whereby either or both may be used for heating the water of the tank.

25 In the drawings, Figure 1 is a view in rear elevation of my composite or double stove and the said hot-water tank or boiler. Fig. 2 is a view in plan representing a part of the coal-burning section of the stove and the gas-burning section, a part of the top plate being 30 removed to show the construction underneath. Fig. 3 is a view in vertical cross-section upon the dotted line of Fig. 2. Fig. 4 is cross-section on the dotted line of Fig. 1.

35 A represents the coal-burning section of the stove, B the gas-burning section thereof, and C the hot-water tank or boiler. It is connected with the coil or other heating device in the fire-pot of the coal-burning section 40 by means of the pipes c c', (shown by dotted lines in Fig. 1,) in which may be cocks for shutting out or disconnecting this section of the stove, and it is connected with the coil b in the gas-burning section of the stove by 45 the pipes b' b', which may also have cocks for forming or breaking the connection with the said coil b. The coil b is contained in the heating-chamber b³ at the rear of the main gas-burning section, (see Figs. 2 and 3,) the 50 said chamber being formed by plates b⁴ b⁵, attached to the back of the main gas-burn-

ing section of the stove and covered by the extension b⁶ of the main top plate, in which there may be one or more small pot-holes b⁷. (See Fig. 2.) The coil is preferably rectangular in shape, and the gas-burner D is arranged beneath it, and the heat from the burning gas rises upward about the coil, circulation being established, when desired, through the flue d' in the back plate of the 60 gas-burning section (see Figs. 2 and 3) to the direct up-flue of the coal-burning section, following the course of the arrows (see Fig. 2)—that is, connecting with the burner-section d² and the flue d³, which connects it with the flue 65 d⁴ of the coal-burning section. The burners D are connected with the gas-supply pipe E by extending downward the section e of the gas-supply pipe and running from it a lateral branch e', (see Fig. 2,) from which extend 70 short pipes e' to the burners, each pipe having a regulating-cock. It will be seen that by this means the water of the boiler may be heated by either the coal-burning section of the stove or by the gas-burning section, or by both, and 75 that when the gas-burning section of the stove alone is used the water of the boiler may be hot or not, as desired.

The coal-burning section is connected with the boiler, as shown in Figs. 1 and 4, by the 80 pipes c c', which connect with the pipes B' B² near the front end of the coal-burning section.

Having thus fully described my invention, I claim and desire to secure by Letters Patent of the United States—

85 In a composite stove, the combination of the boiler C, the coal burning section A, the gas burning section B, the chamber b⁵ at the back of the section B, formed of the plates b⁴ b⁵ and the extension b⁶, the burner D situated in said chamber, the coil b also situated in said chamber, the pipes b' b³ connecting the coil with the boiler C and the pipes c c' from the coal burning section A, connected with the pipes b' b² and containing cocks 90 where by the water may be shut off from the coal burning section if desired, as and for the purposes described.

PERCIVAL W. ELLIOTT.
